UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

DESIGN FOR A HEADLIGHT.

44,469.

Specification for Design.

Patented Aug. 12, 1913.

Application filed April 25, 1913. Serial No. 763,659. Term of patent 14 years.

To all whom it may concern:

Be it known that I, CHARLES W. DAKE, a citizen of the United States, residing at Chicago, in the county of Cook and State of Illinois, have invented a new, original, and ornamental Design for a Headlight, of which the following is the specification, reference being had to the accompanying drawing, forming part thereof.

Figure 1 is a front elevation. Fig. 2 is a plan view. Fig. 3 is a side elevation.

I claim:

The ornamental design for a headlight as shown.

CHARLES W. DAKE.

Witnesses:

MINNIE SUNDFAR,
MINNIE M. LINDENAU.
